UNITED STATES PATENT OFFICE

JAMES MIRLINK, OF BRADLEY, OHIO

ATTACHMENT FOR SUBMARINES AND SHIPS

Application filed April 13, 1928. Serial No. 269,681.

This invention has relation to rescue and escape apparatus for use in connection with submarine vessels and has particular reference to means for rendering efficient and easily operable the devices by which a safety chamber lowered from a floating ship or other vessel adapted for salvage purposes, may be coupled to a sunken submarine vessel, and the crew of the latter afforded safe and reliable means of escape therefrom and ingress to said chambers, and whereby the submarine vessel may be sealed at the exit openings against the entrance of water before or after the escape of the crew.

The invention further relates to the provision of means for so illuminating the safety chamber that its descent may be seen by the divers near the sunken vessel and preparation made for its reception and connection to the latter.

The invention further relates to the provision of means within the safety chamber for affording the occupants the required ease and comfort which their physical condition may demand.

With the specially recited objects in view and others that will appear hereinafter, the invention consists in the features of construction and the combinations of elements herein- after detailed and claimed.

In the accompanying drawings which illustrate a typical and preferred embodiment of the invention,

Figure 1 is a view comprehending in side elevation a sunken submarine vessel, an end view of a floating salvage vessel above the submarine, and a side view or elevation of a safety vessel coupled to the submarine and connected by cables to the salvage vessel;

Figure 2 is a vertical central section of the safety chamber, and a fragmentary longitudinal sectional view of a submarine vessel below the same but disconnected therefrom;

Figure 3 is a sectional view of the lower part of the safety chamber in coupled relation to a submarine;

Figure 4 is a longitudinal sectional view of part of the deck of a submarine vessel having an exit for the escape of the crew; and

Figure 5 is a side view, partly in section of

an equipment for use in connection with sunken submarine vessels lying on the sides.

For the purposes of this invention the deck 1 of a submarine vessel 2 is formed with openings through the double spaced plates 4, 5, 55 and to these openings are fitted thimbles 6, 6' secured by flanges 7 and 8, and bolts 9, 10 to the deck plates. These thimbles or tubes are of sufficient diameter to afford passage therethrough of members of the crew, and 60 project upwardly a few inches above the upper deck plate and a lesser distance below the lower deck plate.

These thimbles or tubes are screw threaded interiorly and are adapted to receive the 65 screw plugs 9 in thimble 6 and in thimble 6', the screw plugs 10 which close and seal the openings through the thimbles against the entrance of water, but which are removable when it is desired or necessary to couple to 70 the vessel the safety chamber.

The latter is designated by the Figure 12, and consists of a hollow casing composed of vertical enclosing walls, and horizontal top and bottom plates. This casing or chamber 75 is of large capacity so as to hold a number of occupants. An air chamber 14 having valve attachments 14a is located at the upper part of the chamber, and the interior of the chamber is furnished with one or more tiers of beds 80 or berths 15 to receive disabled or exhausted members of the crew of a sunken submarine. The chamber or casing is mounted on a soft rubber block 15a by eye bolt connections 17 projecting from the side walls and there is 85 provided a central opening 18, through the floor of the chamber and the rubber block, affording an entry to the chamber. The floor plate 15b is flanged around this opening as at 19, and the opening is provided with a 90 flanged closure cap 20, screw threaded interiorly to engage with screw threads on the outside of the flange. A ring 2' is secured to the closure to enable it to be conveniently attached to and detached from the flange by the 95 occupants of the chamber. Depending from the roof of the safety chamber is a pulley 21, carrying a chain or cable 22, to be used in raising the occupants of the vessel. Eyes 23 are attached to the upper part of its casing 100.

for the connection of chains or cables by which the chamber is raised and lowered. Eyes 24 are also fastened to the sides of the chambers for the attachment of chains or cables 25, having hooks for connection with eyes 26 on the deck of the submarine.

The safety chamber is lowered and raised by a floating vessel 27 equipped with a crane and other appliances necessary for the purpose, which need not be described.

The casing or chamber 12 is intended and adapted to rest on the deck of the submarine, when lowered from the salvage vessel, previously to which operation divers will have descended and located the position of the submarine and communicated with the salvage vessel. The safety chamber 12 carries flood lights 30 suitably positioned on the outside, by means of which its descent can be seen by the divers. When the casing is lowered and swung into proper position by the divers the opening in the center of the rubber block 15 will coincide with and be entered by the projecting thimble 6, which closely fits the opening in the rubber block. The latter will rest on the deck, and being of soft rubber will form a watertight seal. When the safety chamber has been thus coupled to the submarine, the plug 9 will be drawn out of the thimble and free access will be had through the latter to the interior of the safety chamber. It will be understood that the safety chamber is securely fastened to the submarine by the cables 25 and hooks 26. For the removal upward of the screw plug 9, it is provided with hooks 9' on top, and with a boss 9² for the attachment of a wrench.

The plug 9 has hooks 9³ at its lower end for the attachment of a chain or cable, to be used in lifting lifeless occupants of the submarine.

A second screw plug 9⁴ is used to seal the openings from the deck, and prevent the entrance of water to the interior of the submarine after removal or escape of its occupants.

Ordinarily the safety chamber will be lowered to and rest on the deck of the submarine, and has so far been described as intended and adapted for such contingency. To provide for other situations as when the submarine is lying on its side instead of resting on its keel, and when for this reason the deck cannot be reached through the bottom of the safety chamber, in the manner described, the safety chamber may be constructed with a side opening as illustrated in Fig. 5, which is in the form of a projecting pipe section 30, threaded for the attachment of a union 31, coupled to which is a rubber hose 32, which at its outer end is clamped to a pipe section 33, in the end of which adjacent the hose is a threaded plug 34. Another union 35 connects the pipe section 33 to the submarine.

When the submarine is lying on its side

the safety chamber will be connected therewith through the connection above described and the chamber will be entered laterally instead of in a vertical direction.

When not in use the rubber hose 32 can be folded or collapsed and remain attached to the safety chamber.

It is to be understood that the submarine may and should have as many egress openings as there are chambers liable to be occupied by the crew, so that if intercommunication is cut off the safety chamber may be moved from place to place and thus reach all the occupants of the submarine.

What I claim as new is:—

1. In combination with a vessel having a tubular mounting passing through its wall and having a detachable closure within the mounting, life saving apparatus comprising a chamber member provided with an opening of the same diameter as the exterior diameter of the tubular mounting, a block of soft elastic material carried by the chamber member and having an opening registering with the opening of the chamber member, said block being of greater transverse thickness than the height of the edge of the tubular mounting above the outer surface of the wall of the vessel, the opening in the block snugly and slidably receiving the tubular mounting, means for connecting the side walls of the chamber with the wall of the vessel and a closure for the opening in the wall of the chamber and removable therefrom interiorly of the chamber.

2. In combination with a vessel having a tubular mounting passing through its wall and having a detachable closure within the mounting, life saving apparatus comprising a chamber member provided with an opening of the same diameter as the exterior diameter of the tubular mounting, a block of soft elastic material carried by the chamber member and having an opening registering with the opening of the chamber member, said block being of greater transverse thickness than the height of the edge of the tubular mounting above the outer surface of the wall of the vessel, the opening in the block snugly and slidably receiving the tubular mounting, means for connecting the side walls of the chamber with the wall of the vessel, a closure for the opening in the wall of the chamber and removable therefrom interiorly of the chamber and a block and fall hanging pendent from the top wall of the chamber at a point vertically above said opening.

In testimony whereof I affix my signature.

JAMES MIRLINK. 125
